HAIR DRIER

Filed March 8, 1928

UNITED STATES PATENT OFFICE

WILLIAM MEYER, OF CHICAGO, ILLINOIS

HAIR DRIER

Application filed March 8, 1928. Serial No. 259,993.

This invention relates to hair driers and its object is the provision of a generally improved, simple and relatively inexpensive outlet construction for concentrating the 5 drying stream and increasing the speed with which the drying action is effected, and an outlet construction that will confine the discharging drying stream and direct the same more effectively over the head to dry the 10 hair more evenly or uniformly.

The outlet construction of the present invention is also adapted for effectively positioning the head with respect to the discharging stream and for permitting movement of 15 the head relative the drier without impairing the drying action.

For purposes of illustration I have illustrated the invention in connection with the drier more fully disclosed in my co-pending 20 application, Serial No. 211,121, filed August 6, 1927, which application has matured into Patent No. 1,686,024, issued October 2, 1928, but it is to be understood that the invention 25 is not limited to use with or embodiment in that particular drier, but may be used with or embodied in other driers as and where suitable or desired. I have also illustrated the present invention as an attachment and as being adapted for movement into and out 30 of operative position, as well as out of the way when not desired and without removing it from the drier. It is to be understood, however, that the present outlet construction 35 may be embodied as an integral part of the drier, without being adjustable or movable out of operative position, or it may be in the form of an attachment adapted for movement into and out of operative position or for complete removal as desired. Other 40 variations are also contemplated within the scope of the appended claims.

According to the present invention I provide a hooded outlet which is preferably of a size to comfortably receive the head and I 45 form this outlet to confine the drying stream without appreciable loss and to concentrate the same to increase the speed and effectiveness of the drying action. This hood is preferably formed to direct more of the drying stream or to concentrate the stream more

on the parts of the head where the hair is thicker and less down the back of the neck and along the sides where the hair is thinner. Excessive heating down the back of the neck and along those portions of the head where 55 the hair is thinner is avoided and ample heating and/or drying where the hair is thicker is provided.

The invention is illustrated in the accompanying drawing, in which:

Fig. 1 is an end view of the discharge or outlet end of a drier embodying the present invention;

Fig. 2 is a longitudinal section taken on the line 2—2 of Fig. 1;

Fig. 3 is a fragmentary detail section through the outlet or discharge end of the outlet hood, taken on the line 3—3 of Fig. 1; and

Fig. 4 is a fragmentary detail section taken 70 on the line 4—4 of Fig. 2.

The drier shown comprises a generally cylindrical shell 5 having an open outlet end 6. The rear end of the shell 5 is attached at 7 to a generally cylindrical drum 8 which 75 forms a continuation of the inner or rear end of the shell 5. The cross section of the drum 8 and shell 5 may, of course, vary from cylindrical as desired. The drum 8 and shell 5 may be of suitable sheet metal construction, although this may, of course, be varied 80 widely.

At the rear end of the drum 8 is a head or end member 9, suitably secured to the adjacent rear end of the drum 8 at 10. A suitable 85 electric motor 11 is mounted axially or centrally in the head or end member 9, preferably with the revolvable motor shaft 12 disposed axially with respect to the drum 8 and shell 5. The end or head member 9 is also 90 provided with suitable inlet openings 13 through which the air is drawn into the device and discharged longitudinally through the shell 5 toward and from the outlet or discharge end 6.

Arranged forwardly of the motor 11 and mounted marginally in the rear end of the shell 5 is a transverse partition 15. The partition 15 has a conical axially disposed opening 16, the smaller end of which opens rear- 95 100

wardly as shown. The fan or propeller 18 is disposed adjacent the rear of the opening 16, preferably with its forward edge in substantially the plane of the rear end of the opening 16. The propeller 18 is suitably fixed upon the motor shaft 12 so that it will rotate with the motor shaft, upon rotation of the same, drawing air through the rear inlet openings 13 and impelling the same forwardly through the shell and out through the outlet 6.

For the purpose of preventing swirling or circular motion of the air through the device, the shell 5 is provided, forwardly of the partition 15 with suitable anti-swirling members 20. The anti-swirling members 20 may be arranged generally radially within the shell and may be suitably attached or mounted along their rear edges upon the partition 15. A standard or other suitable electric light socket 21 is mounted axially within the shell 5 upon the anti-swirling members 20 and is adapted to receive a lamp 22 which may be a high power electric light or incandescent lamp, such as a nitrogen or high powered tungsten filament lamp. The lamp 22 is provided with a reflector 23 disposed rearward of the lamp and directed forwardly, the lamp 22 being preferably positioned in the focus of the reflector, or otherwise as desired with respect thereto. The reflector 23 is shown as mounted at 24 upon the socket 21 and the periphery of the reflector 23 is preferably spaced at 25 from the inner surface of the shell 5.

A heating coil 26 is shown as mounted upon the anti-swirling members 20 for the purpose of suitably heating the stream of air in its passage from the inlet 13 to and out through the outlet 6.

The drier is provided with a switch 30 and the current supply conductor means (not shown) may be connected to the motor 11, heater 26 and lamp 22 through the switch means 30. The switch 30 is provided with suitable lever means 32 which is preferably adapted for separately controlling the motor, heater and lamp circuits although, of course, the particular circuit connections may be varied. The conductor means is preferably provided with a suitable connector for connection with a standard or other suitable outlet. The device is provided with suitable means 34 for mounting the drier upon an upright stand 35 or other suitable support. The drier is preferably swingable about the pivot 36 and is preferably adjustable up and down vertically to adjust the height or vertical position of the drier.

In operating the drier, the lamp 22 constitutes the source of radiant heat and radiant light. The rays of light and the heat admitted by the lamp 22 are reflected by the reflector 23 and projected outwardly through the outlet end 6.

When the motor circuit is closed, the fan 18 is started and air is drawn in through the inlet openings 13 and projected with the radiant heat and light through the discharge end 6 of the device, and upon the hair and scalp or other surface. The air is blown across the heater 26 which when the heater circuit is closed, heats the stream of air in its passage through the device. The blades or anti-swirling members 20 prevent circular or swirling motion of the air and direct the same in substantially a straight line through the outlet 6.

The outlet construction of the present invention is in the illustrated embodiment, as already pointed out, in the form of a hooded attachment designated generally at 38. The hood 38 which may be of sheet metal, or other suitable construction comprises a generally cylindrical wall 39 closed at its rear end by a radial end wall 40. The end wall 40 has a collar or sleeve 41 which may be formed integrally with the end wall 40 or otherwise attached thereto. The collar 41 is shown as telescoping over the adjacent end of the shell 5 for operative position upon the outer end of the shell 5, as shown. The collar 41 may be and preferably is adapted for sliding movement longitudinally along the outer surface of the shell 5 for moving the hood 38 out of operative position and out of the way rearwardly on the hood when its use is not desired. When the hood 38 is positioned rearwardly out of the way, the outlet 6 may constitute the outlet or discharge end of the drier directly for use wherever use of the hood is not desired. The hood 38 may even be removed entirely for use of the device without the hood and where it is movable on the shell 5 from one position to another it may be held frictionally in its different positions or suitable clamping or other means may be provided for fastening the hood in its different positions.

The forward or outer end of the generally cylindrical wall 39 of the hood terminates along a diagonal or oblique line, as indicated at 48 and extending along the top and down along the sides of the forward end of the generally cylindrical wall 39 is a flange 50. The lower ends of the side portions of the flange 50, which may be rounded at 52 into the forward end of the cylindrical portion 39 are preferably narrower at 53 than the top or upper portion 54 of the flange, the width of the flange preferably decreasing gradually from the median part of the top down along each side to the lower end thereof. The angle of the median upper part or top of the flange 50 to the cylindrical wall 39, as indicated at 56 is also preferably less or sharper than the angles 58 (Fig. 3), between the lower ends of the side portions 53 and the cylindrical wall 39 and the angular relation between the flange 50 and the adjacent end of

the wall 39 preferably decreases or becomes sharper gradually and uniformly from the lower ends 52 to the median part of the top or upper portion 54 of the flange.

8 The outer edge of the flange 50 is preferably dimensioned to comfortably receive the head as indicated in dotted lines at 60 and the lower ends of the opposite sides of the flange 50 terminate short of the bottom of the 10 wall 39, leaving the open bottom 62 of a width suitable to comfortably receive the neck or back portion of the head.

15 The flanged end 50 of the hood forms a concentrating ring for concentrating the drying stream and increasing the speed thereof and the speed of the drying action and at the same time the shape and varying angle of the flange to the cylindrical wall 39 of the hood coupled with the disposition of the outer 20 let 6 with reference thereto as will be explained presently, confines the drying steam and directs the same more effectively over the head to dry the hair more evenly or uniformly. The outlet 6 preferably opens 25 through the rear wall 40 eccentric with reference to the generally cylindrical wall 39 and is disposed closer to the bottom of the hood. This with the enlargement of the wall 39 over the shell 5 provides ample space 30 around the sides and top of the hood for receiving the head and the downward disposition of the outlet 6 provides suitable space or clearance over the top and around the sides of the head for permitting the drying stream 35 to pass around the head. The flange 50 not only confines and concentrates the drying stream at the forward end of the hood, but it deflects the same back effectively along the forward portions of the top and sides of 40 the hair bearing portion of the head.

The varying angular disposition of the flange directs more of the drying stream or concentrates the stream more on the part of the head where the hair is thicker and 45 less along the part of the head where the hair is thinner. The open bottom portion 62 eliminates any objectionable projection or direction of the drying stream down the back of the neck and excessive heating down the 50 back of the neck and along those portions of the head where the hair is thinner is avoided.

For the purpose of deflecting the stream of air beyond its passage through the axial 55 opening 16, the blades or anti-swirling members 20 may be provided with deflectors 70. These deflectors 70 are shown in the form of integral ears struck out of the radial walls of the anti-swirling blades and adapted for 60 deflecting the air out better across the heater 26 to secure a more complete or more uniform heating of the stream of air in its movement past the heater 26. The deflectors 70 need not be integral with the blades 20 and 65 may be otherwise arranged and mounted

within the casing or shell of the device. The present device heats the drying stream better and with less current.

I claim:—

1. In combination, a drier having a casing, 70 means for projecting the body of air through said casing, a rigid outlet hood at the outlet end of said casing of a size to receive the head and to allow the body of air to pass over and past the head, and deflecting means arranged on said hood adjacent the outlet end and spaced from the head to direct the air inwardly and against the head during its outward flow.

2. In combination, a drier having a casing, 80 means for projecting a body of air through said casing, an outlet hood at the outlet end of said casing of a size to receive the head and having an outlet of fixed size spaced from the head to allow the body of air to pass over and past the head, and deflecting means arranged at the forward end of said hood adjacent the outlet and spaced from the head to direct the air inwardly and against the head during its outward flow.

3.. In combination, a drier, a casing therefor, means for projecting a body of air through said casing, an outlet hood at the outlet end of said casing, said hood being enlarged to fit over the head and confine and distribute the drying stream thereover, said hood opening toward and around the head for the discharge of the body of air over and past the head, and means on said hood for concentrating the drying stream, said concentrating means being formed to concentrate the drying stream more along the part of the head where the hair is thicker and less along the back of the neck and along the sides where the hair is thinner.

4. In combination, a drier having a casing, 100 an outlet hood at the outlet of said casing and enlarged to receive the head, and an oblique flange at the forward end of the hood for confining and concentrating the drying stream, 110 said flange being spaced from the head upon arrangement of the hood upon the head and opening toward and around the head for the discharge of the body of air over and past the head.

5. In combination, a drier having a casing, 115 an outlet hood at the outlet of said casing and enlarged to receive the head, and an oblique flange at the forward end of the hood for confining and concentrating the drying stream, 120 said confining and concentrating flange extending along the top and sides of the hood only and open along the bottom to avoid excessive heating down the back of the neck and along those portions of the head where the hair is thinner.

6. In combination, a drier having a casing, 125 means for projecting a body of air through said casing, an outlet hood at the outlet end of said casing, said hood being enlarged to fit

over the head and opening toward and around the head for the discharge of the body of air over and past the head, said hood having a generally cylindrical wall eccentrically disposed at the outlet end of the casing, and a flange along the outer edge of said cylindrical wall for confining and concentrating the drying stream, said flange being inclined inwardly and forwardly in position to depend below the top of the head and forwardly of the front of the head to direct the body of air inward through the hair at the front of the head.

7. In combination, a drier having a casing, an outlet hood at the outlet end of said casing and enlarged to fit over the head, said hood having a generally cylindrical wall eccentrically disposed at the outlet end of the casing, and a flange along the outer edge of said cylindrical wall for confining and concentrating the drying stream, said flange being of varying angularity with respect to the cylindrical wall of the hood and extending along the top and sides only and open at the bottom with the internal angularity of said flange with reference to said cylindrical wall less at the top and increasing down along the opposite sides of the hood.

8. In a device of the class described, the combination of a casing having an outlet opening, an outlet hood on the end of said casing and having an enlarged generally cylindrical wall extending from the casing and disposed eccentrically thereto, said wall terminating at its forward end in a plane oblique to the axis of the drier, and an inwardly directed drying stream confining and concentrating flange extending along the top and sides of said wall and open at the bottom.

9. In a device of the class described, the combination of a casing having an outlet tube, means for blowing a stream of air therethrough, a heater, a reflector and means independently of the casing and outlet tube and independently of the reflector for deflecting the air stream across said heater.

10. In a device of the class described, the combination of a casing, a partition having an axial opening, a fan disposed adjacent the rear of said opening for blowing a stream of air therethrough, a heater forwardly of said opening, and deflector means disposed between said partition and said heater for deflecting the air across said heater.

11. In a device of the class described, the combination of a casing, means for blowing a stream of air therethrough, a heater, means for preventing swirling and circular motion of the air, and means on said last means for deflecting the air across the heater.

12. In a hair drier, the combination of a casing having an outlet, means for projecting a body of air through said casing, an outlet hood disposed at the casing outlet and opening forwardly to receive and fit over the head

with said forward head receiving opening and hood both spaced from the head to permit movement of the body of air over and past the head and out forwardly through said head receiving opening and an inwardly and forwardly inclined flange disposed at said hood outlet in position to depend below the top of the head in the path of movement of the body of air and forwardly of the front of the head when same is positioned within the hood to deflect the body of air inward through the hair at the front of the head in the discharge of the air through said forward hood opening.

13. As an article of manufacture, a hood for hair driers having an inlet and oppositely opening outlet adapted to receive and fit over the head with said outlet and hood, both spaced from the head to permit movement of the drying body over and past the head and out through said head receiving outlet, and an inwardly and forwardly inclined flange disposed at said hood outlet in position to depend below the top of the head in the path of movement of the body of air and forwardly of the front of the head when same is positioned within the hood to deflect the body of air inward through the hair at the front of the head in the discharge of the air through said forward hood opening.

In witness whereof, I hereunto subscribe my name this 2d day of March, 1928.

WILLIAM MEYER.
